OSCILLATOR CONSTRUCTION

Evert M. Ostlund, Montclair, N. J., assignor to
 Federal Telephone and Radio Corporation, New
 York, N. Y., a corporation of Delaware

Application May 24, 1945, Serial No. 595,515

16 Claims. (Cl. 315—39)

1

The present invention relates to the construction of oscillators particularly of the coaxial line type.

To obtain maximum efficiency from an oscillator, the feed-back must be controlled. In internal feed-back arrangements, where energy is fed back through the inter-electrode capacities of the vacuum tubes used, control of the feed-back becomes difficult because the inter-electrode capacities are fixed. External feed-back arrangements have the advantage that they may be tuned, and in general tuned feed-back arrangements provide greater excitation than untuned ones. In order, however, to provide optimum operation over a band of frequencies, the tuning of the feed-back arrangement should be capable of being varied over the band of frequencies covered.

An object of the present invention is the provision of an improved coaxial line oscillator of the external feed-back type.

Another object of the present invention is the provision in an oscillator of improved external inductive feed-back means adapted to be tuned over a band of frequencies.

Another object of the present invention is the provision in an oscillator, of external inductive feed-back means which is correspondingly tuned over a band of frequencies by the tuning of the input and output circuits of the oscillator over said band.

Other and further objects of the present invention will become apparent and the invention will be best understood from the following description of embodiments thereof, reference being had to the drawings, in which:

Fig. 1 is a partially schematic and partially sectional view of a coaxial line oscillator embodying my invention;

Fig. 2 is a section taken along the line 2—2 of Fig. 1;

Fig. 3 is a fragmentary elevational view, partly broken away, of a modification of the structure illustrated in Fig. 1; and

Fig. 4 is a fragmentary sectional view of another modification of the structure illustrated in Fig. 1.

Referring now to Figs. 1 and 2, the coaxial line structure there illustrated includes an electron discharge device or vacuum tube 1 having an anode 2, a grid 3, and a cathode 4. The anode is coupled to a hollow elongated cylindrical conductor 5 and the cathode 4 is coupled through condenser 6 to a similar cylindrical conductor 7. Conductors 5 and 7 are the inner conductors of

2

coaxial lines 8 and 9 respectively whose outer conductors, cylindrical members 10 and 11 are coupled together and completely surround and shield the inner conductors and the tube 1.

Tube 1 is preferably of the type in which the grid and its lead serve as an electrostatic shield between the anode and its lead and the cathode and its leads, as for example, in the lighthouse tube. Grid 3 is connected to a grid disc 12 which extends between flanged portions 13 and 14 respectively of the external conductors 10 and 11 and is separated from said flanged portions by insulation, generally designated by the numeral 15. This arrangement forms a capacity between the grid and the outer conductors 10 and 11. Depending upon the value of this capacity, a certain amount of feed-back may be introduced between the anode coaxial line 8 and the cathode coaxial line 9. Said coaxial lines 8 and 9 are preferably short-circuited at their outer ends by conductive discs 16 and 17 respectively.

In accordance with one embodiment of my invention, external feed-back means are provided as follows: four rods 18, 19, 20 and 21 are symmetrically arranged, as shown in Fig. 1, equidistant from each other between the inner conductors 5 and 7 and the outer conductors 10 and 11 and extending substantially from disc 16 to disc 17 through suitable openings 22 in the grid disc 12. Rods 18—21, being conductors, serve as feed-back means feeding back energy from the anode coaxial line 8 to the cathode coaxial line 9.

Since the oscillator arrangement here described is designed to operate over a band of frequencies, I have provided, in accordance with my invention, means for tuning the coaxial lines 8 and 9 and the feed-back conductors 18—21. For this purpose I prefer to provide slidable discs 23 and 24 in coaxial lines 8 and 9. Each of said discs is conductive and is provided with openings through which the rods 18—21 pass, said openings being provided with spring fingers, generally designated by the numeral 25, which make contact with the rods as discs 23 and 24 are slid therealong. Spring fingers 26 are provided adjacent the perimeter of each of the discs 23 and 24 and make contact with the inner surface of the outer conductors 10 and 11 respectively, while similar fingers 27 are provided at the central opening 28 of discs 23 and 24 to make contact with the inner conductors 5 and 7 respectively.

By varying the position of the discs 23 and 24, the effective length of the various conductors, that is the inner conductors 5 and 7, the outer conductors 8 and 9 and the rods 18—21 may be

varied. By selecting the proper number of rods and their diameters in relation to the other constants of the oscillator, optimum feed-back is obtained over a range of frequencies. The position of discs 23 and 24 may be changed by means of rods 29 and 30 extending through suitable openings in end discs 16 and 17 respectively. These rods are of insulating material.

While in the embodiment illustrated in Figs. 1 and 2, the feed-back is controlled by slideable discs 23 and 24 respectively which simultaneously vary the tuning of the associated coaxial lines 8 and 9, in certain instances it is desirable to have additional independent means for controlling the feed-back. In the modification illustrated in Fig. 3, each of the rods 18-21 is independently tuned by one of four coaxial line tuning stubs 31, each having an inner conductor 32 connected with its associated feed-back rod and whose outer conductor 33 is connected with the outer conductor 11 of the coaxial line. Tuning stubs 31 are each provided with tuning means such as a slideable shorting tuner 34. Adjustment of the position of tuner 34 varies the energy fed back independently of the tuning by discs 23 and 24.

In the other modification illustrated in Fig. 4, independent tuning of the feed-back rods is accomplished by interposing a tuning stub 35 effectively between each of the feed-back rods and the disc 23 so that the rod serves as the inner conductor of the stub and passes through an opening 36 provided in the disc 23 while the outer conductor 37 of the tuning stub is connected with the disc 23 about said opening 36. Adjustment of the tuning element 38 of the stub varies the energy fed back independently of the tuning of the coaxial lines. Similar stubs may be associated in like manner with disc 24.

While I have described hereinabove the details of one construction embodying my invention, it will be obvious to those versed in the art that numerous changes may be made in the details thereof without departing from the teachings of my invention. Therefore, while I have described above the principles of my invention in connection with specific apparatus, it is to be clearly understood that this description is made only by way of example and not as a limitation on the scope of my invention as defined in the accompanying claims.

I claim:

1. A transmission line oscillator comprising an electron discharge device including an anode, cathode, and grid, a cathode transmission line coupled to the cathode, an anode transmission line coupled to the anode, feed-back means comprising a linear conductor operatively associated with both said transmission lines, and movable conductor means connected across said transmission lines and to said linear conductor for tuning the transmission lines and for varying the effective length of the linear conductor to thereby control the feed-back.

2. A coaxial line oscillator comprising an electron discharge device including an anode, cathode, and grid, a cathode inner conductor coupled to the cathode, an anode inner conductor coupled to the anode, outer conductors surrounding said inner conductors and coaxial therewith, said outer conductors being coupled to the grid, feed-back means comprising a single linear conductor member having a portion thereof extending between the cathode inner conductor and its outer conductor and the remainder extending between

the anode inner conductor and its outer conductor.

3. A coaxial line oscillator according to claim 2 wherein said linear conductor member extends parallel to the central axis of said inner and outer conductors.

4. A coaxial line oscillator comprising an electron discharge device including an anode, cathode, and grid, a cathode inner conductor coupled to the cathode, an anode inner conductor coupled to the anode, outer conductors surrounding said inner conductors and coaxial therewith, means capacitively coupling the grid to said outer conductors, feed-back means comprising a single linear conductor member having a portion thereof extending between the cathode inner conductor and its outer conductor and the remainder extending between said anode inner conductor and its outer conductor.

5. A coaxial line oscillator comprising an electron discharge device including an anode, cathode, and grid, a cathode inner conductor coupled to the cathode, an anode inner conductor coupled to the anode, outer conductors surrounding

6. A coaxial line oscillator comprising an electron discharge device including an anode, cathode, and grid, a cathode inner conductor coupled to the cathode, an anode inner conductor coupled to the anode, outer conductors surrounding said inner conductors and coaxial therewith, a conductive disc coupled to said grid and extending toward said outer conductors and forming a capacitive coupling therewith, feed-back means comprising a linear conductor member extending between said cathode inner conductor and its outer conductor and between said anode inner conductor and its outer conductor, said grid disc having openings therein through which said linear conductor member extends.

7. A coaxial line oscillator comprising an electron discharge device including an anode, cathode, and grid, a cathode inner conductor coupled to the cathode, an anode inner conductor coupled to the anode, outer conductors surrounding

8. A coaxial line oscillator comprising an electron discharge device including an anode, cathode, and grid, a cathode inner conductor coupled to the cathode, an anode inner conductor coupled to the anode, outer conductors surrounding said inner conductors and coaxial therewith, said outer conductors being coupled to the grid, feed-back means comprising a plurality of linear conductor members, each having a portion extending between the cathode inner conductor and its outer conductor and the remainder extending between the anode inner conductor and its outer conductor, said linear conductor members being symmetrically disposed about said inner conductors.

9. A transmission line oscillator, comprising an electron discharge device including an anode, cathode, and grid, a cathode transmission line coupled to the cathode and grid, an anode transmission line coupled to the anode and grid, each of said transmission lines including two conductors, feed-back means comprising a linear conductor extending between the conductors of the cathode transmission line and the conductors of the anode transmission line, and means for varying the effective length of said conductors comprising a pair of slideable conductive members, one of said slideable members coupling the conductors of the cathode transmission line to each other and to the linear conductor, and the other of said slideable members coupling the conductors of said anode transmission line to each other and to the linear conductor, said slideable members being adapted to be moved to select the points at which said conductors are coupled to each other.

10. A transmission line oscillator, comprising an electron discharge device including an anode, cathode, and grid, a cathode transmission line coupled to the cathode and grid, an anode transmission line coupled to the anode and grid, each of said transmission lines including two conductors, feed-back means comprising a linear conductor extending between the conductors of the cathode transmission line and the conductors of the anode transmission line, and means for varying the effective length of said conductors comprising a pair of slideable conductive members, one of said slideable members coupling the conductors of the cathode transmission line to each other and to the linear conductor, and the other of said slideable members coupling the conductors of said anode transmission line to each other and to the linear conductor, said slideable members being adapted to be moved to select the points at which said conductors are coupled to each other.

11. A coaxial line oscillator comprising an electron discharge device including an anode, cathode, and grid, a cathode inner conductor coupled to the cathode, an anode inner conductor coupled to the anode, outer conductors

surrounding said inner conductors and coaxial therewith, said outer conductors being coupled to the grid, feed-back means comprising a linear conductor member extending between the cathode inner conductor and its outer conductor and between the anode inner conductor and its outer conductor, and means for varying the effective length of said conductors comprising a pair of slidable conductive members, one of said slidable members coupling the cathode inner conductor, its outer conductor, and the linear conductor, the other of said slidable members coupling the anode inner conductor, its outer conductor, and the linear conductor, said slidable members being adapted to be moved to select the points at which said conductors are coupled to each other.

9. A coaxial line oscillator according to claim 2 further including means for varying the effective length of said conductors comprising a pair of slidable conductive discs each having a central opening therein, the cathode inner conductor passing through one of said openings, and the anode inner conductor passing through another of said openings, means on each of said discs adjacent said opening for contacting the inner conductor within said opening, means on each of said discs adjacent the circumference thereof for contacting the inner surface of the outer conductor thereadjacent, each of said discs further having an opening for the accommodation of said linear conductor, and means on each of said discs adjacent said last-mentioned opening for making contact with said linear conductor.

10. A transmission line oscillator comprising an electron discharge device including an anode, cathode, and grid, a cathode transmission line coupled to the cathode, an anode transmission line coupled to the anode, feed-back means comprising a linear conductor connected to both said transmission lines, separate disc means connected in each transmission line, said disc means being also connected to said linear conductor for varying the effective length of the linear conductor when the lines are tuned to thereby control the feed-back, and means independent of said tuning means for controlling the feed-back comprising a tuning stub having its inner conductor connected with said linear conductor, and means for tuning said stub.

11. A transmission line oscillator according to claim 10 wherein the outer conductor of said stub is connected to the outer conductor of one of said transmission lines.

12. A transmission line oscillator according to claim 7 further including means for independently tuning said linear conductor comprising a tuning stub carried on said slidable member and effectively interposed between slidable member and said linear conductor, said linear conductor forming the inner conductor of said tuning stub.

13. A coaxial line oscillator comprising an electron discharge device including an anode,

cathode, and grid, a cathode inner conductor coupled to the cathode, an anode inner conductor coupled to the anode, outer conductors surrounding said inner conductors and coaxial therewith, a grid disc connected to the grid and coupled to said outer conductors, said disc having openings therein, feed-back means comprising a single linear conductor member having a portion thereof extending between the cathode inner conductor and its outer conductor and the remainder extending between the anode inner conductor and its outer conductor, said linear conductor member extending through an opening in said grid disc.

15. 14. A coaxial line oscillator according to claim 6 in which conductive tuning members are connected across the cathode inner and outer conductors and the anode inner and outer conductors and to the feed-back conductor members 20 and in which the cross section and number of said feed-back conductor members are chosen with respect to other constants of said oscillator so that optimum feed-back is obtained over a predetermined range of frequencies.

25. 15. A transmission line oscillator comprising an electron discharge device including an anode, cathode, and grid, a cathode transmission line coupled to the cathode, an anode transmission line coupled to the anode, feedback means connected between the transmission lines, movable conductors connected across said transmission lines for tuning the transmission lines and conductive connecting means between said feedback means and said conductors for varying the effect 30 of said feedback means when said conductors are moved.

35. 16. A transmission line oscillator comprising an electron discharge device including an anode, cathode, and grid, separate anode and cathode 40 transmission lines coupled between the anode and grid and the cathode and grid respectively, feedback means comprising a linear conductor insulated from the grid and extending through both said transmission lines, movable conductors connected across said transmission lines and to said linear conductor for tuning the transmission lines and for varying the effect of said feed-back means when said transmission lines are 45 tuned.
